UNITED STATES PATENT OFFICE.

ISAAC WEINGART, OF NEW YORK, N. Y., ASSIGNOR TO LEUUMANN, BOESCH
& WEINGART, OF NEW YORK, N. Y., A FIRM.

GARMENT.

No. 845,494.

Specification of Letters' Patent.

Patented Feb. 26, 1907.

Application filed September 12, 1906. Serial No. 334,219.

To all whom it may concern:

Be it known that I, ISAAC WEINGART, a citizen of the United States, and a resident of the city, county, and State of New York, have invented certain new and useful Improvements in Garments, of which the following is a specification.

My object is to make a very simple garment from a plain piece of material without having to cut and shape the same and which may be adjusted to fit properly over the shoulder of the wearer.

In the drawings forming part of this application, Figure 1 is a view showing the garment as it is worn. Fig. 2 is a perspective view of the garment alone. Fig. 3 is an elevation showing the arm-straps. Fig. 4 shows the decorated loops on the shoulder-straps for the tie-string. Fig. 5 shows how the shoulder-straps are brought to the garment by the tie-string; and Fig. 6 shows the style of ornamentation on the edge of the garment.

The garment is formed, preferably, of one piece of material 1, which is placed around the body of the wearer and in which are cut semicircular or other armholes 2 along the top edge of the material. The upper edge of the garment is preferably decorated by an ornamental edge 3, which is formed with a series of loops 4, through which is threaded a tie-string 7, so that the upper part of the garment, which is preferably used as a corset-waist, presents a pleasing appearance.

I provide shoulder-straps 6 for securing the garment, which are preferably made separate of the body and are ornamented and provided with loops 5, similar to the loops on the body, through which the same tie-string 7 is passed as is attached to the body, the tie-string having a continuous fastening in the top edge of the body and in the arm-straps.

When the garment is attached to the wearer, the tie-string is pulled taut and tied in the front, when the straps will be brought down to the body of the garment and, together with the upper edge of the waist, is made to fit snugly to the wearer. I believe I am the first to secure a tie-string to the shoulder-straps to make the same fit to the wearer.

Having described my invention, what I claim is—

A body - garment, having substantially semicircular armholes or recesses in its upper edge, independent shoulder - straps and a gathering-string passing through loops in the upper edge of the garment and loops in said straps, whereby the latter are adjustably secured to the garment.

Signed this 8th day of September, 1906.

ISAAC WEINGART.
